UNITED STATES PATENT OFFICE.

PETER KRUSE, OF NEW YORK, N. Y., ASSIGNOR TO E. W. BLISS COMPANY, OF BROOKLYN, NEW YORK, A CORPORATION OF WEST VIRGINIA.

MACHINE FOR BEADING AND FLANGING CAN-BODIES.

1,176,370.

Specification of Letters Patent.

Patented Mar. 21, 1916.

Application filed July 10, 1912. Serial No. 708,545.

To all whom it may concern:

Be it known that I, PETER KRUSE, a citizen of the United States, residing in the borough of Brooklyn, county of Kings, city and State of New York, have invented certain new and useful Improvements in Machines for Beading and Flanging Can-Bodies, of which the following is a specification.

In the making of tin cans it is customary to feed flat sheets of tin cut to the required size successively to apparatus which first bends up and down the opposite edges to form hooks; then advances the sheet to the point where it is folded around an expanding mandrel called the "horn" in such manner that the hooked edges are inter-hooked, whereupon the horn expands and draws these hooks together, and a ram called the "bumper" then descends and squeezes the inter-engaging hooks against the horn to form the side seam of the can. This ends the work peculiar to the so-called body-forming machine. The subsequent operations depend upon the kind of can being made. For some purposes the can is bottomed at one end and receives a slip cover at the other end or top. For making such cans it is desirable to form a bead just beneath the cover to stiffen the upper part of the can. For applying the bottom the opposite end of the can has to be flanged, that is, its edges turned outwardly in order that it may later be double-seamed to the bottom. For some cans the bead, instead of being at the opposite end from the flange, is adjacent to the same end.

The present invention provides a machine for performing simultaneously, or nearly so, these operations of beading and flanging.

The machine provided by this invention may receive the can body after it is delivered out of the body-forming machine; or the two may be built together so that the can body, after the side-seaming operation, is pushed along on a prolongation of the horn and is then acted on by the mechanisms constituting the present machine.

The machine provided by the present invention comprises exterior beading jaws which, when a can is properly presented, close in upon it, and internal beading jaws in the same plane, which expand within the can while it is held by the encircling outer jaws and indent the sheet metal into a groove in the outer jaws, thereby forming

the bead. While the can is held between the respective beading jaws whereby it is securely clamped, a flanging die is pressed against its projecting end, partly entering the can, and expanding its end portion, whereby it is turned outwardly to form the flange. The beading jaws are then retracted to free the can body and the flanging die recedes carrying the can with it, whereby the can is advanced beyond the plane of the beading jaws, whereupon it is dropped out of the machine. To insure the movement of the can with the receding die one or more ejectors are provided which engage the newly-formed flange and compel it to advance with the flanging die.

The accompanying drawings show a machine embodying this invention, of which—

Figure 1 is a side elevation; Fig. 2 is a vertical transverse section taken on the planes of lines 2—2 in Fig. 1. Fig. 2^a is a sectional fragment of Fig. 2. Fig. 3 is a vertical section taken mainly on the plane of the line 3—3 in Fig. 2. Fig. 4 is a fragmentary transverse section on a larger scale, giving a face view of the beading jaws. Fig. 5 is a section in the planes of the lines 5—5 in Fig. 4 showing the machine at the end of the beading and seaming operations. Fig. 6 is a face view of the beading jaws in their retracted or inactive position, the supporting parts being omitted. Figs. 7 and 8 are a face view and plan of the wedge for expanding the inner beading jaws. Figs. 9 and 10 are a face view and horizontal section of one of these jaws. Fig. 11 is a fragmentary elevation similar to part of Fig. 1, but showing the machine in a different position. Fig. 12 is a fragmentary elevation looking in the direction 12 in Fig. 11.

In Fig. 1 let A represent the horn of the body-forming machine, or an extension of such horn; or it may be any guide along which the successive can bodies are fed by any suitable means. So far as concerns the present invention they might be fed by hand. B shows a fragment of the frame of the body-forming machine; or it might be any other suitable supporting framework. C is the main frame of the present machine.

D is a shaft which may be regarded as the driving shaft and may carry a belt pulley or any other suitable means for imparting

- movement. As shown in Fig. 1 this shaft communicates motion through miter gears $a a'$ to a shaft E which in turn communicates movement through miter gears $b b'$ 5 to a shaft F. The shafts D and F revolve synchronously. The shaft D carries an eccentric G (Fig. 3) which is encircled by an eccentric strap connecting by a link c to one arm of a lever d , the opposite or longer 10 arm of which connects by a link e to any suitable part of a slide H whereby this slide is reciprocated regularly by the operation of the eccentric. The slide H slides in ways h formed on the top of the frame C, as best 15 shown in Fig. 2. The link e connects with an adjustable piece f clamped to the slide by a block g which is adjustable by a screw i whereby the slide may be set forward or backward, as may be required (see Fig. 3).
- 20 The shaft F carries a cam J, the groove of which acts upon a roller carried on the lower arm of a lever j , the upper arm of which connects by a link k to a yoke l engaging a rod K, which has sliding bearings in the 25 opposite ends of the slide H. For adjusting this rod longitudinally set-nuts $m m$ are provided. The front end of the rod is supported by a plate n fastened on the front of the slide H.
- 30 The flanging die L is carried on the front end of the slide H against the plate n and the rod K moves freely through a central hole in this die.
- The beading mechanism comprises outer 35 beading jaws M M shown as four in number, which encircle the can, and inner beading jaws P P, (Fig. 6) also shown as four in number, which are adapted to fit within the can. The outer jaws have in their inner 40 faces a circumferential groove; and the inner jaws have on their outer faces a similar but smaller circumferential rib in the same plane with said groove, so that when the respective jaws are forced together the 45 rib and groove coöperate to form the bead. The inner jaws are supported by the end of the mandrel or horn A, (Fig. 5) being overlaid by a plate p fastened by screws q to the horn or mandrel. Each jaw is con- 50 fined to a radial movement by being formed with a rib r , Figs. 9 and 10, which slides in a radial groove in the end of the mandrel A. The sections are moved by an expander Q, Figs. 7 and 8, which has essentially four 55 wedge-shaped faces engaging the inner faces of the four jaws. These faces are dovetails s engaging dovetailed grooves s' in the jaws, as shown in Figs. 8 to 10. The expander Q is pressed out by a spring t to contract the 60 jaws and is pushed in by the rod K to expand the jaws. The outer jaws M M, which are preferably alternated in arrangement with the inner jaws, are also moved radially and simultaneously. They are shown in 65 their inner positions in Fig. 4 and in their outer positions in Fig. 6. The jaws are mounted on radial slides M' mounted in a special frame R. The jaws are drawn outwardly by springs $u u$. They are forced inwardly by a cam ring S shown best in Fig. 6, which is given an oscillatory movement whereby the cam surfaces or notches $v v$ are brought into or out of engagement with rollers $v' v'$ carried on their respective slides M' . The ring S is connected to an arm S' which connects by a rod T to a crank U conveniently carried on miter gear a' , Fig. 1. On the down-stroke of the crank a downward pull is communicated through the rod T which positively pulls down on the arm S' and oscillates the ring S to the position where the cam notches v coincide with the rollers v' , thereby opening the jaws M M as shown in Fig. 6. The opposite movement oscillates the ring to cause the cams v to force the jaws inwardly; and as in this movement the jaws grasp and embrace the can body, it is desirable, to allow for slight variations in the diameter of the can or the thickness of the sheet metal, that this active movement of the ring S should be performed yieldingly in order that the jaws may not be pressed in too far. For this purpose the connecting rod T is made telescopic or collapsible, in manner best shown in Fig. 2^a. The rod is divided into two parts between which is a stiff spring S^2 . The upper part of the rod enters into a sleeve T' making a sliding fit therewith, while the lower part of the sleeve T' is screw-threaded and engages the threaded lower end of the rod. The sleeve has a slot into which projects a pin w carried by the upper section of the rod, the slot being sufficiently long to allow for the desired yielding movement. In the down-stroke the end of the slot remains in contact with the pin w as shown in Fig. 2 and thus the movement imparted is positive; while on the up-stroke the thrust is communicated through the spring S^2 and is yielding. For adjusting the length of the connecting rod T the sleeve T' is screwed up or down and locked by a nut w' .
- The operation is as follows:—Assuming the machine to be built as a continuation of an ordinary can-body-forming machine, the can body from the latter is pushed along the horn A by means of a reciprocating feeding pusher V, Fig. 5, or in any other manner. The can body is shown at X in Fig. 5. The cam ring S in its oscillations then forces inward the jaws M M until they tightly grip the can body and hold it, forming thereby an annular anvil. Meanwhile the slide H and rod K have been approaching the can body from the right in Figs. 1 and 5, and before the flanging die L reaches the can body the advancing end of the rod K strikes the expander Q and pushes it back 13.

to about the position shown in Fig. 5, where by the inner beading jaws P P are moved outward so that the beading ribs on these jaws force or crimp the metal into the beading groove in the outer jaws M, whereby the can body is beaded. The instant after this beading operation is completed the further advancing movement of the slide II brings the flanging die L into action. This die is of usual construction, having a central central portion which enters within the projecting end of the can body and which terminates in a quarter-round groove whereby the sheet metal is expanded and turned outward to form the flange. The flanging groove terminates as usual in an abrupt shoulder which is struck by the edge of the sheet metal and forms the flange. At the completion of the flanging movement the parts are in the positions shown in Fig. 6. Thereupon the rod K retracts and releases the expander Q which is then projected by its spring T so that its dovetailed wedging faces act to draw inwardly the inner beading jaws P P. At or about the same time the return reciprocating movement of the ring S releases the outer jaws M M, which are drawn outwardly by their springs u u. The can body is now free from engagement with the respective beading jaws. Thereupon the slide II executes its return movement, moving to the right in Figs. 1 and 3, and the can body is carried with it, whereby it is advanced out beyond the plane of the beading jaws. Ordinarily the can body will have sufficient adhesion to the flanging die L to move with it; but in case it should not so move it is engaged by an ejector jaw or jaws W, shown best in Figs. 11 and 12, the inward projection of which is sufficient to engage forward of the flange on the can body, so that it is adapted to pull the can body off the end of the horn. Thus the can body is carried backward with the slide II until free from the beading jaws, whereupon it is caused to fall out of the machine through the wide space formed by the retractile movement of the slide II. In this position the can body is released by the retraction of the ejector W. For this purpose the ejector is mounted on a lever W', the tail or short arm y of which is engaged by a stationary cam piece Y mounted on the frame C. In Figs. 11 and 12 the arm y is shown as coming into engagement with this fixed cam Y. On the completion of the movement the inclined cam face Y rocks the lever W' and retracts the ejector W, whereupon the can body falls out. On the next forward movement the ejector is first restored by its spring u'. The ejector projects only far enough to engage the flange and not far enough to strike the protruding end of the next can body to be flanged.

It will be understood that my invention

is not limited to all the details of construction which have been shown and described but that its embodiment may be susceptible to considerable variation in matters of design, construction and proportion, and by 70 the substitution of mechanical equivalents.

Reference is made to my application Serial No. 751,661 filed February 27, 1933, the mechanism of which is partly identical with that of the present application, so far as 75 concerns the beading mechanism. The novel features of the flanging mechanism herein disclosed, independent of their relation to the flanging mechanism herein claimed, have been claimed in said later application. 80

What I claim is—

1. A machine for flanging can bodies comprising inner and outer segmental jaws adapted to grip a can body between them so as to hold it against longitudinal displacement, and a flanging die movable subsequently against the projecting end of the can body which it is to head by said jaws. 85

2. A machine for beading and flanging can bodies comprising segmental beading jaws adapted to embrace the can body within them, segmental beading jaws adapted to expand within the can body and grip it against the external jaws, a flanging die, a slide carrying said die, and means for reciprocating said slide, adapted to advance it to cause said die to act against the projecting end of the can body while it is held by said jaws. 90

3. A machine for beading and flanging can bodies comprising segmental beading jaws adapted to embrace the can body within them, segmental beading jaws adapted to expand within the can body and grip it against the external jaws, a flanging die, a slide carrying said die, and means for reciprocating said slide, adapted to cause said die to act against the projecting end of the can body while the latter is held in said jaws. 100

4. A machine for beading and flanging can bodies comprising segmental beading jaws adapted to embrace the can body within them, segmental beading jaws adapted to expand within the can body and grip it against the external jaws, a flanging die, a slide carrying said die, a rod for actuating said internal jaws moving through said die, 110 and means for reciprocating said rod and said slide to first bend the can body and afterward flange it. 115

5. A machine for beading and flanging can bodies comprising segmental beading jaws adapted to embrace the can body within them, segmental beading jaws adapted to expand within the can body and grip it against the external jaws, an expander with 120 said internal jaws for actuating them, a flanging die, a slide carrying said die, a reciprocating rod for actuating said expander moving through said die, and a driving mechanism for reciprocating said rod and said slide, adapted to first advance said rod 125 and said slide. 130

to expand said internal jaws and to subsequently advance said slide to cause the flanging die to operate.

6. A machine for beading and flanging can bodies, comprising beading and flanging means and an ejector adapted to admit the unflanged body and engage the flange when formed thereon, and means for reciprocating it to withdraw the body from the beading means.

7. A machine for flanging can bodies, comprising holding means for embracing and holding the can body during the flanging, and a flanging die, having an ejector movable with the flanging die adapted to engage in front of the flange on the flanged body to pull the latter free from said holding means as the flanging die retracts.

8. A machine for beading and flanging can bodies, comprising a flanging die and having an ejector movable with the flanging die adapted to engage the flange on the flanged body to feed the latter out as the flanging die retracts, and means for displacing said ejector at the end of its travel to release the body.

9. A machine for flanging can bodies, comprising a reciprocating flanging die, an ejector movable with the flanging die comprising a lever having a portion adapted to engage the flange on the flanged body, whereby to feed the latter out as the flanging die retracts, and a stationary cam engaged by said lever to displace the latter and disengage it from the can body to release the latter.

10. A machine for flanging can bodies comprising gripping means for holding a body with its end projecting, adapted to release it after the flanging operation, a flanging die movable against such projecting end to turn it outward to form a flange, and an ejector adapted to engage in front of such out-turned flange and movable backward to pull the flanged body away from its flanging position after the action of the flanging die.

11. A machine for flanging can bodies comprising gripping means for holding a body against the action of a flanging die, such flanging die movable against the end of the body to turn it outward, the gripping means adapted thereupon to release the body, and an ejector adapted to engage in front of such out-turned flange and movable backward with the flanging die to pull the flanged body away from the flanging position as the flanging die retracts.

12. A can body machine comprising means for holding a can body with its end projecting, and beading, creasing and flanging means adapted to act in immediate succession to both bead and flange the can body while it is so held.

13. Mechanism for shaping can bodies comprising a mandrel, external jaws movable inwardly to embrace the can body, mechanism for simultaneously moving said jaws inwardly comprising an oscillatory cam for imparting movement to the respective jaws, and driving mechanism for oscillating said cam comprising a yielding part adapted to yield when the active movement of said cam is completed.

14. Mechanism for shaping can bodies comprising a mandrel, external jaws movable inwardly to embrace the can body, mechanism for simultaneously moving said jaws inwardly comprising an oscillatory cam for imparting movement to the respective jaws, and driving mechanism for oscillating said cam comprising a part adapted to yield at the end of the active movement of said cam and to impart a positive retractile movement thereto.

15. Mechanism for shaping can bodies comprising a mandrel, external jaws movable inwardly to embrace the can body, and mechanism for simultaneously moving said jaws inwardly comprising an oscillatory ring having cam surfaces for imparting movement to the respective jaws, and driving mechanism for oscillating said ring comprising a link having a spring member adapted to yield at the end of the active stroke of the ring.

16. Mechanism for shaping can bodies comprising a mandrel, external jaws movable inwardly to embrace the can body, and mechanism for simultaneously moving said jaws inwardly comprising an oscillatory ring having cam surfaces for imparting movement to the respective jaws, and driving mechanism for oscillating said ring comprising a link having a spring member adapted to yield at the end of the active stroke of the ring and to communicate an unyielding retractile movement to the ring.

In witness whereof, I have hereunto signed my name in the presence of two subscribing witnesses.

PETER KRUSE.
